US0D1021248S

(12) **United States Design Patent** (10) Patent No.: **US D1,021,248 S**
(45) Date of Patent: ** Apr. 2, 2024

- (54) **SHAVING RAZOR CARTRIDGE**
(71) Applicant: **The Gillette Company LLC**, Boston, MA (US)
(72) Inventors: **Michael Tejpal Verasamy**, Mountain View, CA (US); **Ashok Bakul Patel**, Needham, MA (US); **Michael Hal Bruno**, Burlington, MA (US); **Jack Anthony Washington**, Mendon, MA (US); **Matthew Michael Long**, Methuen, MA (US); **Zachary Oliver Veugen**, Fall River, MA (US); **Robert Harold Johnson**, Hingham, MA (US); **Jessy Lee Cusack**, Attleboro, MA (US)
(73) Assignee: **The Gillette Company LLC**, Boston, MA (US)
(**) Term: **15 Years**
(21) Appl. No.: **29/850,785**
(22) Filed: **Aug. 23, 2022**

Related U.S. Application Data

- (62) Division of application No. 29/717,377, filed on Dec. 17, 2019, now Pat. No. Des. 965,221, which is a division of application No. 29/642,546, filed on Mar. 30, 2018, now Pat. No. Des. 874,061.
(51) **LOC (14) Cl. 28-03**
(52) **U.S. Cl. USPC D28/47**

(57) **CLAIM**

The ornamental design for a shaving razor cartridge, as shown and described.

DESCRIPTION

FIG. 1 is a top perspective view of a shaving razor cartridge showing our new design;

FIG. 2 is a top view thereof;

FIG. 3 is a bottom view thereof;

FIG. 4 is a right view thereof;

FIG. 5 is a left view thereof;

FIG. 6 is a rear view thereof;

FIG. 7 is a front view thereof; and,

FIG. 8 is a bottom perspective view thereof.

The broken lines illustrate portions of the shaving razor cartridge and form no part of the claimed design.

1 Claim, 6 Drawing Sheets
